CLAIM

The ornamental design for a transmission device for chainless bicycle, as shown and described.

DESCRIPTION

FIG. 1 shows a perspective view of the present design.

FIG. 2 shows a front view of the present design,

FIG. 3 shows a rear view of the present design.

FIG. 4 shows a left side view of the present design

FIG. 5 shows a right side view of the present design.

FIG. 6 shows a top view of the present design; and,

FIG. 7 shows a bottom view of the present design.
